(57) **CLAIM**

The ornamental design for a closure for a container, as shown and described.

DESCRIPTION

FIG. 1 is a top perspective view of a closure for a container according to our new design;

FIG. 2 is bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines shown in the drawings depict portions of the closure for a container that form no part of the claimed design. The dot-dot-dash broken line(s) define the bounds of the claimed design and form no part thereof.
